UNITED STATES PATENT OFFICE.

JAMES H. TAYLOR, SR., AND JULIUS B. TAYLOR, OF TOLEDO, OHIO.

GEAR.

1,170,707.

Specification of Letters Patent.

Patented Feb. 8, 1916.

Application filed October 6, 1915. Serial No. 54,325.

To all whom it may concern:

Be it known that we, JAMES H. TAYLOR, Sr., and JULIUS B. TAYLOR, citizens of the United States, residing at Toledo, in the 5 county of Lucas and State of Ohio, have invented certain new and useful Improvements in Gears; and we do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

In certain classes of machinery it is desirable to revolve a rotatable body in one direction for a time and to then reverse the rotation, as, for instance, in the operation 20 of the washing cylinder of a washing machine.

Our invention relates to gears of this character, and is designed to furnish a mechanism which will automatically convert 25 a continuous rotary motion of a driving shaft into a regularly reversed motion of a driven member. In washing machines in which the clothes are mechanically rubbed in a revolving cylinder, this reversal of rotation is particularly desirable 30 for the reason that when the cylinder has been revolved for a short time the clothes become packed in the cylinder and thus the efficiency of the machine is greatly diminished.

We have, in the specification, by way of 35 illustration, shown our invention as applied to and connected with the rotary cylinder of a washing machine, which cylinder, by means of our invention, is automatically caused to rotate for a short time in one direction and to then revolve in the opposite direction.

To these ends our invention consists of the 40 devices, construction and arrangement of parts hereinafter described, and shown and illustrated in the accompanying drawings, in which—

Figure 1 is a front elevation of our gear 45 with a portion of the case in which it is mounted broken away; Fig. 2, a vertical central sectional elevation of the same seen from the right in Fig. 1, and Fig. 3, a

front elevation of a washing machine provided with our gear.

55

Like numerals of reference indicate like parts in all the views.

In the drawings, 1 is a driving shaft provided with a suitable pulley not shown, and, if desired with a balance wheel. This shaft 60 is journaled in bearings on the machine and at opposite sides of the circular casing 2 which is suitably secured to the front of the machine and incloses the gears hereinafter described. Upon the shaft 1 is a sleeve 3, 65 movable longitudinally upon the shaft but revoluble therewith by reason of a spline-and-groove arrangement, such for instance, as pins 4 projecting radially from the shaft into elongated recesses 5 in the sleeve. It 70 will be seen that the pins and recesses cause the sleeve to revolve with the shaft but permit a limited longitudinal movement of the sleeve upon the shaft. At each end of the sleeve and rigid therewith is a clutch-member 6 adapted to engage a corresponding clutch-member 7 rigidly connected with or forming part of beveled pinions 8 loose upon the shaft 1. It will be seen that as the sleeve is moved longitudinally the members 80 of one or the other of the clutches will be operatively connected according to the direction in which the sleeve is shifted. This movement at regular intervals of the sleeve in one direction and then in the other direction, is accomplished by means of the devices now to be described.

9 is a shaft rigidly connected at one end with the cylinder 10 to be rotated, and at its other end rigidly and centrally connected 90 with a dish shaped gear-wheel 11, the beveled teeth of which are in mesh with both the pinions 8. Upon the face of the gear 11 next to the sleeve 3 is a spiral groove 12 extending from near its center to near the rim 95 of the gear, the bottom of the groove at each end sloping outwardly. This groove is engaged by a pin 13 projecting from one end of a lever 14, fulcrumed as at 15, upon a brace or support 16 bolted or otherwise 100 rigidly secured to the inside of the casing 2 at its lower side. The opposite end of the lever 14 is pivotally connected, as at 17, with one end of a link 18 the other end of which, through an elongated slot, which affords considerable lost motion, is connected,

105

as at 19, with a lever 20. This lever is fulcrumed at its lower end, as at 21, upon the brace 16. The lever 20 is recessed near its lower end, as at 22, to receive loosely the lower end of a lever 23, fulcrumed, as at 24, upon the brace 16. The upper end of this lever is notched as at 25, the notch being engaged with a rib or ring 26 which encircles and is rigid with the sleeve 3 at its middle.

10 27 is a weight carried by the lever 20. In the present construction, for illustration, the weight is pivotally suspended from the lever near its upper end, as at 28, and has a recess in its side to receive the lever the sides of 15 the recess forming stops which limit the swing of the weight upon its pivotal support. It will be seen that the driving shaft being in motion and one of the clutches 6-7 being engaged, the gear 11 will be revolved 20 and the pin 13 will traverse the spiral groove 12 to the right or to the left, depending upon the direction in which the gear 11 is rotated. The lever 14 being thus caused to swing upon its pivot the link 18 is moved until the 25 end of its slot engages the pivot-pin 19 on the lever 20. This lever is now, just before the pin 13 reaches the end of the spiral grooves, pulled or pushed, as the case may be, into upright position and is then by force 30 of the weight 27 caused to swing upon its pivot to the limit of its throw. The recess 22 in the lower end of lever 20, being engaged with the lower end of the lever 23, by its throw and the impact of weight 27 35 causes the upper end of the lever 23 to quickly slide the sleeve 3 out of engagement with one clutch and into engagement with the other clutch, which now, through its pinion 8, imparts a reversed rotation to the gear 11 and to its attached cylinder 10. If by any means the reversing gear fails to act, the pin 13, through the wedge-like action of the inclined floor of the spiral groove at its ends, emerges from the groove and now 40 rides upon the annular ungrooved portion of the plate. To prevent the pin 13 from re-entering the spiral groove at the end of its course before the completion of the shifting of the sleeve and the reversal of the rotation of the gear 11, the lever 14 is provided 45 at its lower end with a laterally projecting weight 14^a which holds the upper end of the lever and the pin away from premature engagement with any neighboring convolution 50 of the groove.

55 29 is a hand-lever fulcrumed, as at 30, in the case 1 and having a notch 31 positioned and adapted to receive the ring 25 when the sleeve 3 is central between the two pinions 60 8 and when both clutches are disengaged. A set-screw 32 serves to hold the hand-lever elevated and out of engagement with the sleeve 2 when the machine is in operation. By moving the lever into engagement with 65 the ring 25 the driving shaft may continue

to run without imparting any movement to the gear 11.

Having described our invention, what we claim and desire to secure by Letters Patent, is—

1. A gear of the described character, comprising a driving shaft, a sleeve revoluble with and longitudinally movable upon the shaft, a pinion at each end of the sleeve and loose upon the shaft, clutch-members for 75 engaging the sleeve with the pinions, a gear-wheel engaged at opposite sides with the pinions and having a spirally grooved side, a weighted lever, connections between the lever and said spiral groove and connections 80 intermediate the lever and the sleeve.

2. A gear of the described character comprising a driving shaft, a sleeve revoluble with and slidable upon the shaft, pinions loose upon the shaft, a gear-wheel in mesh 85 at its opposite sides with the pinions and having a spiral groove, and means controlled by the spiral groove for reciprocating the sleeve upon the shaft to engage the sleeve with either of said pinions.

3. In a gear of the described character, a gear-wheel having in its side a spiral groove, a shaft having rotation constant in one direction, pinions loose upon the shaft and in mesh with the gear-wheel at its opposite 95 sides, clutches adapted to operatively engage either of said pinions with said shaft, and means controlled by the spiral groove for alternately actuating said clutches.

4. In a gear of the described character, a 100 shaft, a sleeve revoluble with and slidable upon the shaft, a pinion loose upon the shaft near each end of the sleeve, clutches for engaging the sleeve with either of said pinions, a gear-wheel engaged with both said pinions 105 and having in its side a spiral groove, a lever having one end engaged with the groove, another lever having one end engaged with said sleeve, and operable connections intermediate said two levers.

5. In a gear of the described character, a 110 shaft, a sleeve revoluble with and slidable upon the shaft, a pinion loose upon the shaft near each end of the sleeve, clutches for engaging the sleeve with either of said pinions, a gear-wheel engaged with both 115 said pinions and having in its side a spiral groove, a lever having one end engaged with the groove, another lever having one end engaged with said sleeve, a third lever fulcrumed at its lower end and having a weight at its upper end, the second and third levers mentioned being operatively connected near their lower ends, and a link which connects the lever first mentioned with the third mentioned lever.

6. In a gear of the described character, a driving shaft, a sleeve slidable upon and revoluble with said shaft, pinions loose upon said shaft, a spirally grooved gear-wheel in 120

mesh at its opposite sides with said pinions, clutch-members upon said pinions, corresponding clutch-members upon opposite ends of said sleeve, devices controlled by 5 said groove for alternately engaging said clutches, and means for holding said clutches disengaged while permitting the rotation of the sleeve.

7. In a gear of the described character, a 10 gear-wheel having a spiral groove in its side, a shaft, pinions loose upon the shaft and engaged with the gear-wheel at its opposite sides, a lever having one end engaged with said spiral groove and carrying at its other 15 end a weight, and devices actuated by the swing of said lever for throwing either of said pinions into operative connection with its shaft.

8. In a gear of the described character, a 20 gear-wheel having a spiral groove in its

side, a shaft, pinions loose upon the shaft and engaged with the gear-wheel at its opposite sides, a lever having at one end a member engaged with said spiral groove, and devices connected with the other end 25 of the lever for throwing either of said pinions into operative connection with its shaft, whereby the rotation of the gear-wheel is regularly reversed, combined with means for preventing the reengagement of said member with the spiral groove after emerging 30 from the groove and before the reverse movement of the gear.

In testimony whereof we affix our signatures in presence of two witnesses.
